US00D744817S

(12) **United States Design Patent**
Hyakutake et al.

(10) **Patent No.:** **US D744,817 S**
(45) **Date of Patent:** **** Dec. 8, 2015**

(54) **JOINT FOR CONNECTION**

(71) Applicant: **ADAMANT KOGYO CO., LTD.**,
Tokyo (JP)

(72) Inventors: **Yasuhiro Hyakutake**, Tokyo (JP);
Shinichi Takeda, Tokyo (JP); **Yusuke**
Akiyama, Tokyo (JP)

(73) Assignee: **ADAMANT KOGYO CO., LTD.**, Tokyo
(JP)

(**) Term: **14 Years**

(21) Appl. No.: **29/421,933**

(22) Filed: **Oct. 23, 2012**

(30) **Foreign Application Priority Data**

Apr. 24, 2012 (JP) 2012-009460

(51) **LOC (10) Cl.** **08-08**

(57) **CLAIM**

The ornamental design for a joint for connection, as shown and described.

DESCRIPTION

FIG. 1 is a front view of a joint for connection showing our new design, which is identical to the rear view;

FIG. 2 is a right side view thereof;

FIG. 3 is a left side view thereof;

FIG. 4 is a top plan view thereof, which is identical to the bottom view;

FIG. 5 is a sectional view taken along line 5-5 in FIG. 1,

FIG. 6 is a sectional view taken along line 6-6 in FIG. 4; and

FIG. 7 is a perspective view thereof; and,

FIG. 8 is another perspective view showing the joint for connection in a state of use.

The broken lines shown in FIG. 8 represent the environment of the claimed design and form no part thereof.

1 Claim, 8 Drawing Sheets
